CHART HOLDER

Albert McMinn Hunter, Philadelphia, Pa.

Application April 21, 1937, Serial No. 138,280

2 Claims. (Cl. 129—16)

This invention relates to chart holders, and more particularly to a supporting frame especially designed and constructed for carrying interest computing charts and supporting these charts in an efficient manner whereby easy access may be had to the charts for the purpose of reading the same.

Another object of this invention is the provision of a simple and efficient means for hingedly supporting the computing charts which are carried by the frame so as to permit the charts to be swung from a substantially upright position for reading purposes and at the same time permit these charts to be swung downwardly to rest upon a supporting plate in a substantially horizontal position.

A further object of this invention is the production of a simple and efficient means for removably supporting a series of stacked computing charts upon a supporting frame in such a manner as to firmly anchor the charts in engagement with the frame and also permit the removal of the stacked charts for the purpose of replenishing the charts should occasion arise.

A still further object of this invention is the production of a simple and efficient adjustable means constituting a rest for the hinged supporting plate, which hinged supporting plate is adapted to support the charts when they are in a turned down or substantially horizontal position.

Another object of this invention is the production of a simple and efficient means for supporting the current interest chart upon the top of the supporting frame.

In the drawings:—

Figure 1 is a side elevation of the improved interest computing chart holder;

Figure 2 is a front elevation thereof, certain parts being broken away;

Figure 3 is a rear elevation of the holder;

Figure 4 is a perspective view of the current interest chart supporting plate which is adapted to be removably secured to the main frame;

Figure 5 is an enlarged vertical section taken on line 5—5 of Figure 2;

Figure 6 is a vertical sectional view taken on line 6—6 of Figure 3;

Figure 7 is a horizontal sectional view taken on line 7—7 of Figure 6;

Figure 8 is a longitudinal sectional view through the lower portion of the main frame illustrating the removable parts in separated relation with respect to the frame;

Figure 9 is a perspective view of one end of

one of the interest computing charts illustrating the hinge flap structure;

Figure 10 is a sectional perspective view of a portion of the front end of the main frame illustrating one forward corner thereof and also illustrating the manner in which the chart supporting tray is pressed from the metal constituting the main frame.

By referring to the drawings, it will be seen that A designates the main frame which is adapted to support a series of interest computing charts B, the main frame being also adapted to support a current interest chart supporting plate C, as illustrated in Figure 1.

The frame A preferably comprises a metal body 15 consisting of a metal front plate 10 which terminates in a rearwardly extending bridge portion 11 and is then depressed to provide a tray 12. The tray 12 is preferably supported at an angle inclining downwardly toward the front end of the frame A, as shown clearly in Figures 6 and 8, and this tray 12 terminates in an upwardly extending rearwardly inclined wall 13 to provide a back rest for the chart sheets 14 of the chart series B. The frame A also comprises side plates 15 which may be secured in any suitable or desired manner to the sides of the tray 12 and the rear wall 13 is braced by means of side plates 16 shown in Figure 1. The rear wall 13, however, extends slightly above the bracing plate 16, as is shown in Figure 3, for the purpose hereinafter described, thereby providing an extending tongue portion 17. The side plates 15 may be provided with inturned flanges 18 to which are secured supporting knobs 19 in any suitable or desired manner, these knobs being preferably located at the four corners of the main frame A. Secured to the front plate 10 is a vertically adjustable rest plate 20 which extends across the front of the frame A, as shown in Figures 6 and 7, and the front plate 10 is also provided near its ends with a series of apertures 21 into which apertures 21 may fit the securing bolts 22 for locking the rest plate 20 in a vertically adjusted position, the rest plate having a rearwardly turned flange 23 at its upper end. A name plate 24 may also be secured in place by the bolts 22, such as is shown in Figure 6. Through this adjustment the rest plate 20 may be vertically adjusted when desired.

As is shown in Figures 6 and 7, suitable transverse box-like braces 25 may be utilized and may be secured to the side plates 15 for bracing the frame A.

The front wall 10 is provided with a pair of apertures 26 which are in alignment with similar

apertures 27 formed in the front wall 28 of the tray 12. The rear wall 29 is also provided with smaller apertures 30 in alignment with the apertures 27 and 28. The rear apertures 30 in the 5 wall 29 are adapted to receive the rear ends of the anchoring bolts 31 which anchoring bolts support the series of interest computing charts B, the forward screw heads 32 of the bolts 31 being in alignment with the apertures 27 and 26 in order 10 to permit a screw driver to be inserted through the apertures 26 and 27 when the plates 20 and 24 are removed.

The bolts 31 are arranged in spaced relation and extend through the front clamping plate 33 15 the bottom hinge portion 34 of the hinged supporting plate 35 and also the spacing plates 36, as shown. The bolts 31 also pass through the apertures in the lower ends of the chart plates 14, the chart plates being closely arranged and 20 stacked one against the other, these chart plates in turn being clamped in close nested relation by means of a follower plate 37 through which the bolts 31 are threaded whereby the bolts may be rotated to firmly clamp the parts together as 25 will be obvious by considering Figure 6. The rear ends of the bolts 31 extend through the apertures 38, as previously described, and receive the cap nuts 39 and washers 39 upon the rear face of the plate 29. A lock nut 40 is carried by each 30 bolt 31, which lock nut engages the inner face of the plate 29 for locking the bolts 31 in anchored relation upon the plate 29 and firmly holding the stacked computer plates B in proper relation against removal from the frame. When it is 35 desired to remove the series of computer plates 14 from the frame, they may be bodily lifted therefrom by removing the plates 20 and 24 from the frame A, placing a screw driver into engagement with the screw heads 32 of the bolts 31 to 40 hold the bolts 31 against rotation, loosening the lock nuts 40 and removing the cap nuts 38, whereby the series of computing plates B may be bodily lifted out of the frame, as illustrated in Figure 8. When the nuts 38 and 40 are in proper locking position, however, the series of computer plates 45 will be firmly held within the tray 12 against removal as is shown in Figure 6. By means of this structure, the parts may be readily disassembled and at the same time, the series of computer 50 plates will be firmly held in position although secured only at their rear ends through the medium of the bolts 31 in cooperation with the nuts 38 and 40.

The computer plates 14 are preferably of a 55 special construction, each plate 14 being provided with a specially constructed base portion consisting of a pair of fabric strips 41 engaging opposite sides of the computer plates 14, as shown in Figure 9, and firmly secured thereto adjacent 60 the lower edge, the fabric strips being then drawn together to provide a hinging web 42, and being provided with an intermediate reinforcing filler 43 arranged in spaced relation to the lower edge of the plate 14, the filler portion as well as the covering fabric portion being provided with apertures 44 to permit the passing of the bolts 31 therethrough as is illustrated in Figures 6 and 7. This construction will provide a flexing portion 65 between the lower edge of the plate 14 and the anchoring base so as to permit the chart plates to be readily hinged or swung from an upright position shown in full lines in Figure 1, to a substantially horizontal position shown by dotted

lines in Figure 1. When the plates 14 are arranged in a substantially upright position they are slightly inclined rearwardly to permit the plates to remain in a proper reading position, and the hinged supporting plate 35 previously described normally acts as a cover for the front computer plate 14 when arranged in a substantially upright position. This hinge supporting plate, however, may be swung downwardly to rest upon the upper edge of the rest plate 24 and constitutes a supporting table for the computing plates 14 when they are swung downwardly. 10

The plates 14 preferably contain subject matter constituting a computation of interest on any amount from \$100 to \$300 at whatever rate may 15 be required. The present invention, however, does not deal with this particular arrangement of computation, but resides in the construction of the frame and other structural features for supporting the computing plates in proper and convenient position for reference. 20

In conjunction with the frame A, I also provide a removable plate which carries a chart or card upon which is printed the current interest rate. The card is indicated by the numeral 45 and the 25 frame is indicated by the letter C. This frame is provided with side flanges 46 which constitute track-ways for supporting the card 45. The lower end of the plate is provided with laterally extending ears 47 which are bent rearwardly to 30 provide inturned track flanges 48 to fit over the upwardly extending tongue 17 of the rear plate 13 previously described. In this way, the plate C may be readily attached to or removed from the main frame A when desired. The plate C is offset 35 as indicated at 49, so as to rest upon the upper edge of the plate 13.

It should be understood that certain detail changes in the mechanical construction may be employed without departing from the spirit of 40 the invention, so long as such changes fall within the scope of the appended claims.

Having described the invention, what I claim as new is:—

1. A device of the class described comprising a 45 frame having a tray formed therein extending in an inclined relation, a series of charts arranged in clamped relation, securing bolts passing through the charts and holding the charts in clamped assembled relation, said tray having a 50 rear wall provided with apertures for receiving said bolts, and means engaging the rear ends of said bolts for locking said bolts in engagement with the rear wall of said tray, whereby the series of charts will be firmly held within the length of 55 said tray.

2. A device of the class described comprising a frame having a depressed tray arranged in an inclined position, said tray being inclined upwardly toward its rear end, a series of charts 60 mounted within the tray, clamping bolts passing through the lower ends of the charts, a follower plate carried by the clamping bolts for clamping the charts in packed relation, said tray having a rear wall provided with a plurality of apertures 65 for receiving the rear ends of said bolts, nuts engaging the rear extremities of said bolts adjacent the outer face of said wall, and lock nuts engaging the inner face of said wall for locking said bolts in firm engagement with the wall and firmly holding the lower ends of the chart within said tray. 70
